US00D913374S

(12) **United States Design Patent** (10) **Patent No.:** **US D913,374 S**
(45) **Date of Patent:** **** Mar. 16, 2021**

(54) **DIGITAL SIGNAGE**

(71) Applicant: **LG ELECTRONICS INC.**, Seoul (KR)
(72) Inventors: **Yoonkyeong Lee**, Seoul (KR); **Yongho Lee**, Seoul (KR); **Hewon Kihl**, Seoul (KR)
(73) Assignee: **LG ELECTRONICS INC.**, Seoul (KR)

(**) Term: **15 Years**

(21) Appl. No.: **35/508,218**

(22) Filed: **Apr. 16, 2019**

(80) **Hague Agreement Data**

Int. Filing Date: **Apr. 16, 2019**

Int. Reg. No.: **DM/204941**

Int. Reg. Date: **Apr. 16, 2019**

Int. Reg. Pub. Date: **Dec. 27, 2019**

(30) **Foreign Application Priority Data**

Oct. 24, 2018 (KR) 30-2018-0049035

(51) **LOC (13) Cl.** **20-02**

(52) **U.S. Cl.**

USPC **D20/41**
